H. FALLA

CAN OPENER

Filed June 18, 1926

Patented July 5, 1927.

1,634,493

UNITED STATES PATENT OFFICE.

HEDLEY FALLA, OF MILFORD, NEW HAMPSHIRE.

CAN OPENER.

Application filed June 18, 1926. Serial No. 116,965.

The object of this invention is to provide a can opener which will make a cut in the end wall of the can, close to the side wall, suitable guiding means being provided, and means which will turn outwardly the ragged edge of the metal, adjacent to the side wall of the can, incident to the cutting operation.

A further object is to provide a device of this type which shall include a cutting tool, and a yoke member to which the tool is pivoted,—said yoke member having the particular construction indicated below, in order to provide not only for guiding the tool, but for the positive bending over of the cut edge adjacent to the side wall of the can.

With the foregoing and other objects in view, the invention consists in the novel construction and arrangement of elements described, illustrated and claimed, it being understood that modifications may be made within the scope of the claims without departing from the spirit of the invention.

In the accompanying drawings forming part of this application,

Figure 1 is a perspective view of the device.

Figure 2 is a view in elevation showing the tool as applied to the can, a portion of which appears in dotted lines, the cut edge being shown as having been turned over.

Figure 3 is a view similar to Figure 2, the cutting element being in another position.

Figure 4 is a fragmentary view showing the tool, or a portion thereof, in elevation, and showing a portion of the can in vertical section.

Figure 5 is a perspective view of the yoke member detached, and in inverted position.

In carrying out the invention, I provide a tool including the handle 10, the shank 11, and the blade 12, the latter having a cutting edge and a heel portion.

A pivot 13 connects the shank and blade with a yoke of special construction and including the long side portion or arm 14, and the shorter arm or side portion 15, the latter being roughened or serrated on its under side, as shown at 16, in order to prevent slipping action. Connected or formed with arm 15 is a guide member 17 adapted to contact with the outer surface of the wall of the can, this wall being designated 18, and the implement is thus guided and held in

position for making the cut in the top or end of the can, close to the side wall. At the point where the yoke merges into the guard or guide member 17, a shoulder 16' is formed, and the latter rides on the upper edge of the can.

In Figures 3 and 4 it will be observed that the lower portion 14' of the arm 14 extends downwardly beyond the lower portion of arm 15, and therefore overlaps the upper edge of the can, and engages the depressed top 20, the portion 14' riding along the inner cut edge, sometimes constituting a ragged edge, and bending the latter outwardly to the dotted line position shown at 21 in Figure 2 and elsewhere. This is an important feature of the invention, for the reason that after the cut has been made in a well defined position and close to the edge of the can, the cut edge is rendered harmless, so that no injury to the hand of the operator can occur, from this cause. A bevel is formed at 22, and this portion contacts with the cut edge of the top 20, and tends to prevent the latter from curling upwardly to an undue extent.

Having described the invention what is claimed is:—

1. In a can opener, a cutting blade and shank portion, and a yoke within which the shank portion is pivoted, a downwardly extending guide carried by one arm of the yoke, for engaging the outer side of the can, the middle portion of the yoke and the remaining arm extending below the lower edge of the arm first named and adapted to engage the outer cut edge of the can top and bend it over, incident to the cutting operation.

2. In a can opener, a cutting blade and shank portion, and a yoke within which the shank portion is pivoted, a downwardly extending guide carried by one arm of the yoke, a shoulder being provided on the under side of said arm adjacent to the guide, the shoulder being adapted to engage the upper edge of a can, the other arm of the yoke extending below the lower edge of the arm first named, and being of greater length, and adapted to bend over the outer cut edge of the can top.

In testimony whereof I affix my signature.

HEDLEY FALLA.
